William A. Owen

UNITED STATES PATENT OFFICE

WILLIAM ARTHUR OWEN, OF TOLEDO, OHIO

TOURNIQUET

Application filed December 7, 1929. Serial No. 412,361.

This invention relates to tourniquets and an object is to produce a simple and efficient tourniquet in which liability of injury to the patient due to slipping of the tourniquet 5 while in use, is obviated.

A further object is to provide a tourniquet which is so constructed and arranged that an immediate release thereof may be effected by the manipulation of a single element which 10 may be readily operated by one hand so as to leave the other hand free for use.

Other objects and advantages will herein-after appear and by way of illustration but not of limitation, the invention is shown in 15 the accompanying drawings, in which:—

Figure 1 is a side elevation of the trigger frame for the flexible tourniquet band; Fig. 20 Figure 2 is a vertical sectional elevation of the frame shown in Figure 1 showing the trigger in band-engaging position; Figure 3 is a rear end view of the frame and associated parts; Figure 4 is a transverse sectional elevation of the device taken through the trigger; Figure 5 is a top plan view of the device; 25 and Figure 6 is a horizontal sectional view through the frame looking down upon the band plate.

The illustrated embodiment of the invention 30 comprises a tourniquet having a flexible, elastic band 5 preferably of pure gum rubber which is adapted to encircle an arm or leg. An end of the band 5 is anchored to a frame 1 which consists of a pair of plates suitably connected by a number of rivets. As 35 shown a pair of removable bolts 11 are connected at opposite ends to the plates and retain a clamping plate 12 in position, the plate being formed with suitable sockets to receive the removable bolts 11 so that the greater portion of the bolts are disposed beneath the outer surface of the plate 12 and endwise movement of the plate is prevented. As shown, the under side of the plate is provided with prongs which bite into an end of 40 the band 5 securely to hold the same in place.

Pivoted intermediate its ends on a collar 6 rigidly mounted on a pin 7 is a trigger 2, the upper part of which projects above the frame. The under end of the trigger 2 is formed with a pair of teeth at the forwardly

inclined front or toe position thereof. These teeth will bite into the free end portion 4 of the flexible band 5 after the same has been drawn through the frame between the clamping plate 12 and the under end of the trigger 55 2, the tendency of the band 5 to be withdrawn from the frame 1 is prevented by the toothed end of the trigger in cooperation with the plate 12.

In order normally to hold the trigger 2 in 60 substantially vertical position, a leaf spring 3 is rigidly secured to the trigger adjacent the outer end by a pin 14 and the opposite end of the spring loosely encircles a pin 8 carried by the frame 1 and disposed rearwardly of the trigger.

From the arrangement shown in Figure 2 friction will be imposed upon the band 65 substantially simultaneous with the release of the band by the toothed toe portion of the trigger. The heel of the trigger directly in rear of the toothed toe will bear upon the band after or substantially at the time of its release by the teeth and thereby will exert a slight restraining friction which would prevent the band from abruptly snapping or jerking loose from the frame.

It is manifest that the free end of the band 5 may be inserted over a guide roller 9 on a pin 10 and between the trigger 2 and plate 12. After the band has been adjusted sufficiently tight, no adjustment or manipulation is necessary to hold it in that position, as will be apparent. When it is desired to release the band 5, the trigger is rotated slowly in a counterclockwise direction (Fig. 2) against the tension of the spring 3 and the band 5 will be released without any substantial jerk. Actuation of the trigger 2 75 80 85 90 95 may be effected by the thumb or a finger without difficulty. As shown a pin 13 in rear of the trigger 2 limits its counterclockwise movement.

When the elastic band 5 becomes worn it 95 may be replaced by a new one. This may be readily effected by removing the bolts 11 to free the band from the anchoring plate 12.

Numerous changes in details of construction, arrangement and operation may be ef- 100

fected without departing from the spirit of the invention.

I claim:

1. A tourniquet comprising a frame, a flexible strip, means to anchor one end of said strip to said frame, a manually operable trigger pivoted to said frame, a toe portion on the inner end of said trigger, a heel portion on the inner end of said trigger in rear of said toe portion, the free end of said strip being loosely inserted between the inner end of said trigger and said anchoring means, a gripping surface in said toe portion engageable with said strip for preventing reverse movement thereof, and a surface on said heel portion engageable with said strip upon releasing movement of said trigger substantially at the period of release by said gripping surface.
2. A tourniquet comprising a frame, an elastic strip, detachable means for anchoring one end of said strip to said frame, a manually operable trigger pivoted intermediate its ends to said frame, a toe portion on the inner end of said trigger, the free end of said strip being inserted into the frame beneath said toe portion, gripping teeth in said toe portion engageable with said strip for preventing reverse movement thereof, and spring means normally urging said trigger into strip-engaging position.

WILLIAM ARTHUR OWEN.
